UNITED STATES PATENT OFFICE.

WILLIS D. RIGGS, OF ASHLAND, NEBRASKA.

BORING DEVICE.

1,102,078.

Specification of Letters Patent. Patented June 30, 1914.

Application filed August 5, 1913. Serial No. 783,128.

To all whom it may concern:

Be it known that I, WILLIS D. RIGGS, a citizen of the United States, residing at Ashland, in the county of Saunders and State of 5 Nebraska, have invented new and useful Improvements in Boring Devices, of which the following is a specification.

The invention relates to a boring device, and more particularly to the class of earth 10 augers.

The primary object of the invention is the provision of a device of this character wherein the sinking of casings or tubings within river beds or in the ground for constructing bridges or other superstructures 15 will be expedited, the device being designed to collect the dirt cut so that the same can be removed from the hole by the dumping of the dirt from the bucket or barrel of the said 20 device after the same has been removed from the hole.

Another object of the invention is the provision of a device of this character wherein the auger or the cutter is rotated or 25 driven in a novel manner so as to assure the proper cutting action for severing the earth strata, the loose earth being delivered into a bucket or barrel which is rotated through the medium of a gear connection and is free 30 to slide longitudinally within a casing so that the depth of the hole can be varied as the occasion may require.

A further object of the invention is the provision of a device of this character which 35 is of novel form, and readily and easily operated.

A still further object of the invention is the provision of a device of this character which is simple in construction, reliable and 40 efficient in operation, and inexpensive in manufacture.

With these and other objects in view, the invention consists in the construction, combination and arrangement of parts as will be 45 hereinafter fully described, illustrated in the accompanying drawings, and pointed out in the claims hereunto appended.

In the drawings:—Figure 1 is a side elevation of a device constructed in accordance 50 with the invention, the same being shown

ready for use. Fig. 2 is a vertical longitudinal sectional view thereof. Fig. 3 is a bottom plan view. Fig. 4 is a sectional view on the line 4—4 of Fig. 1. Fig. 5 is a sectional view on the line 5—5 of Fig. 1. Fig. 6 is a sectional view on the line 6—6 of Fig. 3.

Similar reference characters indicate corresponding parts throughout the several views in the drawings.

Referring to the drawings by numerals, the device comprises a cylindrical casing 10 which may be of any desirable length and is formed in its bottom 11 with a central opening 12 through which is adapted to work a 65 tubular bucket or barrel 13, the lower end or bottom of which includes a stationary semi-circular shaped section 14 and a swinging semi-circular shaped section 15 forming a drop door, the stationary or permanent 70 section 14 being provided with an entrance slot 16, while mounted exteriorly of the said section 14 parallel with one edge of the slot 16 and partly projecting thereover is a cutting blade 17 which is adapted to cut into 75 the earth and to direct the same through the slot 16 into the bucket or barrel 13 for collection therein, the said bucket or barrel 13 being rotated in a manner presently described.

Loosely surrounding the bucket or barrel 13 and arranged within the casing 10 is a ring-like cog gear or wheel 18 which will be hereinafter termed the bull wheel, the same being formed at diametrically opposite points with notches 19 in which engage guide angle irons 20, the same being fixed exteriorly to the bucket or barrel 13 at diametrically opposite points thereof and are disposed longitudinally thereof throughout 90 the length of the same so that the said bucket or barrel 13 is free to move longitudinally within the casing 10 through the opening 12 in the bottom 11 thereof without disturbing the bull wheel 18 which when rotated will 95 impart similar movement to the bucket or barrel.

Journaled within the casing 10 at diametrically opposite points of the bull wheel 18 are cog gears or pinions 21 and 22 re- 100

spectively, the latter pinion serving as an idler and is fixed to a stud shaft 23 suitably journaled within the casing, while the pinion 21 is fixed to a driving shaft 24 journaled in brackets or bearings 25 secured to the inner face of the casing 10, the shaft 24 being disposed longitudinally within the latter and has fixed to its upper or outer end a beveled gear 26, the same meshing with a beveled pinion 27 secured to a driving shaft 28 journaled in the casing 10 at right angles to the shaft 24, and this driving shaft 28 projects exteriorly of the casing and is connected in any suitable manner with a motor 15 for rotating the same. The cog gears or pinions 21 and 22 mesh with the bull wheel 18 so that the bucket or barrel 13 will be rotated within the casing 10 when the driving shaft 28 is active, the said bull wheel 18 being formed with an outer peripheral flange 29 which overhangs the gears or pinions 21 and 22 so as to sustain the said bull wheel in alinement therewith and to prevent displacement of the said bull wheel in one direction on the sliding of the bucket or barrel 13 longitudinally within the casing.

The inner or lower ends of the irons 20 are formed with out-turned abutment shoulders 30 which are adapted to engage the bull wheel 18 when the bucket or barrel is being lifted or removed from the casing 10, and in this manner the said bull wheel is disengaged from the pinions 21 and 22 on the removal of the bucket or barrel from the casing.

The door section 15 at a point therein is formed with a notch 31 which is arranged in the path of movement of a latch member comprising a lever 32 formed with opposed semi-circular shaped swells 33 and 34 respectively, the latter swell being of considerably less size than the swell 33 and corresponds with the size of the notch 31 in the section 15, while the swell 33 is of considerably greater size than the said notch 31, and this latch member is supported upon a pivot 35 mounted in a bearing 36 formed on the barrel or bucket 13 so that on the swinging of the lever 32 in one direction the swell 33 will be thrown in alinement with the notch 31 and by reason of the size of the swell 33 the section 15 will be locked against opening movement. Now, on swinging the lever 32 in the reverse direction the swell 34 will be brought into alinement with the notch 31 in the section 15 and said swell being the same size as the said notch will permit the door section 15 to swing to open position so that the contents of the bucket 55 or barrel can be readily dumped through the bottom thereof.

The section 15 of the bottom of the bucket or barrel 13 is connected to the section 14 through the medium of hinges 37, thus per-

mitting the swinging of the said section 15 65 to open or closed position.

In the use of the device the casing 10 is brought to rest by its bottom 11 contacting with the river bed or the earth surface, it being understood of course that the bucket 70 or barrel 13 is arranged within the said casing and the motor connected with the driving shaft 28 is started so that the said bucket or barrel will be rotated, and during this action the blade 17 will cut into the earth 75 or river bed, thereby severing or cutting the dirt which will be forced through the slot 16 in the bottom of the bucket or barrel 13 to be deposited within the latter. When the bucket or barrel 13 has been filled with loose 80 dirt or partly filled to any degree the same is removed from the casing 10 and thereafter the latch member which is normally in locking position is released to permit the opening of the door section 15 which permits the dumping of the contents of the bucket or barrel. When the bucket or barrel 13 is rotated and the blade 17 is cutting the earth it will form a hole within the earth or river bed so as to permit the driving or 90 sinking of a casing or tube within the said hole for the erection of a superstructure or bridge.

What is claimed is:—

1. A device of the class described comprising a casing having a central opening in its bottom, a barrel movable longitudinally in said casing and projected through the opening, a cutter carried by the bottom of the barrel, means for rotating the barrel, 95 and a drop door formed in the bottom of the barrel.

2. A device of the class described comprising a casing having a central opening in its bottom, a barrel movable longitudinally 105 in said casing and projected through the opening, a cutter carried by the bottom of the barrel, means for rotating the barrel, and a drop door formed in the bottom of the barrel, the said barrel having a slot in 110 its bottom directly over the cutter for the filling of the barrel with earth severed by said cutter.

3. A device of the class described comprising a casing having a central opening in 115 its bottom, a barrel movable longitudinally in said casing and projected through the opening, a cutter carried by the bottom of the barrel, a gear loosely surrounding the said barrel, pinions journaled in the casing 120 and meshing with the gear, and means for driving one of the pinions to impart movement to the gear for rotating the barrel.

4. A device of the class described comprising a casing having a central opening in 125 its bottom, a barrel movable longitudinally in said casing and projected through the opening, a cutter carried by the bottom of

the barrel, a gear loosely surrounding the said barrel, pinions journaled in the casting and meshing with the gear, means for driving one of the pinions to impart movement to the gear for rotating the barrel, and guides formed on the barrel and slidable through the gear.

In testimony whereof I affix my signature in presence of two witnesses.

WILLIS D. RIGGS.
